UNITED STATES PATENT OFFICE

2,187,664

MECHANICAL ROSARY

John L. Rogus, Hazleton, Pa.

Application March 8, 1939, Serial No. 260,653

1 Claim. (Cl. 235—83)

This invention appertains to new and useful improvements in rosaries such as are used by prayers.

The principal object of the present invention is to provide a mechanical rosary which will in use eliminate the necessity of the prayer keeping count of the prayers by holding the successive beads.

Another important object of the invention is to provide a mechanical rosary which will require the prayer to merely press a button upon the completion of each prayer with the result that the device will keep count of the prayers said and to the end that the prayer's concentration need not be distracted by directing intermittent attention to the placement of his fingers on the beads of the rosary.

Other objects and advantages of the invention will become apparent to the reader of the following specification.

In the drawings:

Figure 1 represents a front elevational view of the device.

Figure 2 is a front elevational view with the window removed and a part in section.

Figure 3 is a section on the line 3—3 of Figure 1 showing certain parts in elevation.

Figure 4 is a plan view of the case with the mechanism removed.

Figure 5 is a bottom plan view of the ratchet wheel.

Figure 6 is a front elevational view with parts broken away of a slightly modified form of the invention.

Referring to the drawings wherein like numerals designate like parts, it can be seen that the device includes a case 5 having the side walls 6 and the bottom wall 7. Numeral 8 represents a transparent lid which can be suitably secured over the open top of the case 5. The top 8 can have the painted or otherwise opaque portion *a* and the centrally located painted or otherwise opaque portion *b*, leaving the annular clear portion *c* through which the annular arrangement of beads or elements simulating beads and denoted by numeral 9 can be seen, these elements 9 being located on the frame or dial plate 10. The dial plate 10 is formed with openings through which the bolts 12 are disposed, these bolts being threaded into the bottom 7 of the case 5. The bolts have spacers 13 thereon for spacing the plate 10 from the bottom 7 of the case 5.

The plate 10 has the centrally located opening 14 upwardly through which extends the stub shaft 15, the lower end of which is threadedly

disposed as at 16 into a threaded opening in the bottom 7.

Rotatably mounted on the shaft or bolt 15 is the ratchet wheel 17 which has a tapered hub 18 for wedged arrangement into the collar 19 and this collar 19 carries the laterally disposed pointer 20 which terminates at a point underlying the clear portion *c* of the top 8 and is cooperative with the bead-like elements 9, the circular line of which terminates in the representation 21 of a crucifix.

The opening 14 in the dial plate 10 accommodates the collar 19 and between the collar 19 and the head of the bolt 15 is the coiled compression spring 22. A rib 23 rises from the bottom 7 of the case 5 and is adapted to be lightly struck by the radially disposed and depending ribs 24 on the bottom of the ratchet wheel 17.

As shown in Figure 2, one side wall 6 of the case 5 has a lug 25 extending inwardly therefrom and apertured to slidably receive the rod 26, which has the stop collar 27 thereon. Between the stop collar 27 and the lug 25 is the coiled compression spring 28.

A knob or button 29 is slidably disposed against the said side wall 6 and has the stem 30 extending therefrom and through the slot 31 in the side wall. The rod 26 is secured to or merges with the stem 30 and carries the strip spring member 32 which bears against the pawl 33, the latter being pivotally secured as at 34 to the inner end of the stem 30. The stem 30 has the fixed collar 35 thereon to limit outward movement of the stem 30.

It can be seen that the catch 36 operates against the ratchet wheel 17 to prevent return of the ratchet wheel while the pawl 33 is in action.

Obviously, the device can be manufactured very small, for instance in the size of a prayer book, if desired, and the button 29 can be operated by the thumb of the hand holding the device. However, it is to be understood that this device can be manufactured in any size desired. It can be manufactured in quite large sizes for use in churches or use before an entire congregation.

As the button 29 is pushed, each push will feed the indicator hand 20 one bead 9, and when the indicator hand 20 has moved to a point completing one decade, one of the ribs 24 will ride over the single rib 23 on the bottom 7 of the shell 5 and produce a sound or jolt of a mild nature which will quietly inform the prayer that he or she is starting on another decade.

A slightly modified form of the invention is shown in Figure 6. In this form of the inven-

tion the case 38 is formed with an arcuate-shaped slot or sight opening 39, and instead of having the rosary carrier fixed as in the form of the invention shown in Figure 1, the representation 40 of the rosary is carried by a rotor such as a disk 41. In this form of the invention the indicating hand or pointer is denoted by numeral 42 and is fixed. This pointer 42 is carried by the bar 43 which is provided with enlarged end portions 44 suitably bolted in position as at 45. In this form of the invention the rosary carrying disk 41 is suitably secured to the shaft 15 and rotates with the shaft 15 and ratchet 17. (See Figures 2 and 3.)

15 While the foregoing specification sets forth the invention in specific terms, it is to be understood that numerous changes in the shape, size and materials may be resorted to without departing from the spirit and scope of the invention as claimed hereinafter.

Having described the invention, what is claimed as new is—

A mechanical rosary comprising a case, a front dial for the case, said dial being stationarily mounted and formed with a centralized opening, a fixed shaft in the case projecting through the opening, a ratchet wheel slidably and rotatably mounted on the shaft, ratchet means for driving the ratchet wheel, a collar mounted for movement with the ratchet wheel, a pointer extending from said collar, spring means interposed between one end portion of the shaft and the collar, said ratchet wheel being provided with radially disposed ribs, and a stationary rib member in the path of the first mentioned ribs, said collar being yieldable against the tension of the spring to permit the rib members on the wheel to snap over the stationary rib and produce annunciation.

JOHN L. ROGUS.
